CLAIM

The ornamental design for a mobile phone, as shown and described.

DESCRIPTION

FIG. 1 is a front view of a mobile phone showing our new design;

FIG. 2 is a rear view of the mobile phone of FIG. 1; FIG. 3 is a left side view of the mobile phone of FIG. 1; FIG. 4 is a right side view of the mobile phone of FIG. 1; FIG. 5 is a top view of the mobile phone of FIG. 1; FIG. 6 is a bottom view of the mobile phone of FIG. 1; FIG. 7 is a perspective view of the front and right side of the mobile phone of FIG. 1; and,

FIG. 8 is a perspective view of the rear and left side of the mobile phone of FIG. 1; and, FIG. 9 is a partially enlarged view of the portion encircled and marked with A in FIG. 3.

The ornamental design which is claimed is shown in solid lines in the drawings. The broken lines in the drawings form no part of the claimed design. All shade lines in the drawings show contour and not surface ornamentation.

1 Claim, 8 Drawing Sheets
